UNITED STATES PATENT OFFICE.

JOHAN SKINDERVIKEN, OF CHICAGO, ILLINOIS, ASSIGNOR TO S-B ELECTRIC COMPANY,
OF CHICAGO, ILLINOIS, A CORPORATION OF ILLINOIS.

TELEPHONE SYSTEM AND THE LIKE.

1,236,613.

Specification of Letters Patent. Patented Aug. 14, 1917.

Application filed May 8, 1916. Serial No. 96,205.

To all whom it may concern:

Be it known that I, JOHAN SKINDERVIKEN, a subject of the King of Norway, residing at Chicago, in the county of Cook and State of Illinois, have invented certain new and useful Improvements in Telephone Systems and the like, of which the following is a specification.

The present invention has to do with improvements in party line telephone systems. The features of the invention are very well adapted for use in conjunction with party line systems for rural service, but it will presently appear that the features are in no wise limited to this particular class of service.

In the usual type of party line system, the establishment of a local circuit between two subscribers or stations ties up the entire party line, so that, as long as such first established connection is maintained, it is not possible to establish any other separate local circuits on such party line. Consequently, the capacity of the entire party line is limited to the carrying on of a single conversation at one time, and this is true regardless of the number of subscribers or stations which may be connected into the party line.

One of the objects of the present invention is to provide a system wherein a number of separate or independent circuits may be simultaneously established and maintained on a single party line, so that two or more local and private conversations may be simultaneously conducted on said line. This will not only greatly increase the capacity of the line, but will also greatly improve the service from the standpoint of the individual subscriber, because in many cases it will be possible for him to call and converse privately with the desired party, while other conversations are being simultaneously conducted on other portions of the line. Furthermore, the transmission is improved, because the induction affecting the transmission is confined to the induction on the section of line actually in use.

It frequently happens that one subscriber on the line is desirous of securing a private talking connection to another subscriber whose station is already in service, but that such private connection cannot be obtained. One of the objects of this invention is to provide means whereby a calling party may ring a party whose station is already in

service so as to permit an urgent call to be delivered. This feature of the invention also has reference to the provision of an arrangement whereby any station may at any time call central, so that central may receive or deliver an urgent message at any time.

Another feature of the invention has reference to the provision of an arrangement whereby the party line may be divided up, by a very simple operation, into two or more temporary private circuits, each circuit being maintained for the time being independently of the other private circuits, provision being made, nevertheless, for immediate connection of any individual subscriber to central, and provision also being made for the instantaneous changing or modification of the several circuits so temporarily established.

Another object of the invention is to greatly simplify and improve certain of the individual pieces of mechanism which go to make up the entire system.

Other objects and uses will appear from a detailed description of the invention, which consists in the features of construction and combinations of parts hereinafter described and claimed.

Referring to the drawings:

Figure 1 shows diagrammatically a typical eight-party line, including a connection to central, the connections at one station being shown in detail. The circuit shown in Fig. 1 is a metallic circuit in which each station is bridged onto the line;

Fig. 2 shows an eight-party line also embodying the features of the present invention, the connections at one of the stations being shown in detail, but in the arrangement shown in Fig. 2 a grounded circuit is illustrated;

Fig. 3 shows diagrammatically a system similar to that shown in Fig. 1, with the exception that it is modified in certain respects which will presently appear; and

Fig. 4 shows one form of mechanism for direct attachment to a telephone instrument, said mechanism embodying the selector and line restorer contacts in convenient form.

Before proceeding to describe in detail either of the circuits diagrammatically illustrated, I will state that each station is provided with what I will designate a "line-restorer", and with a "selector". The function of the selector is to determine the directions

in which a ring and a conversation will travel along the party line to or from the station in question. For example, when the selector is thrown into one position, the 5 station is so connected that its ringing mechanism will function along one portion of the party line, whereas its talking mechanism will function along the other or opposite portion of the party line, and by reversing 10 the position of the selector, these connections are respectively reversed. The function of the line restorer is to open or close the line-circuit so as to cut the party line at the station in question, to thereby permit the 15 selector to control the connecting of the ringing and talking mechanisms in opposite directions as just set forth. Such line-restorer may be conveniently operated by the operation of the receiver hook, so that the 20 raising of the receiver hook will cause the line to be opened, whereas the lowering of the receiver hook will again close the party line circuit.

Referring now to Fig. 1, the party line 25 therein shown includes the wires 4 and 5 which extend out from the central station A to the individual stations B, C, D, E, F, G, H and J. For purposes of convenience I shall call the wire 4 the tip wire, and the 30 wire 5 the sleeve wire. The connections of the station E are shown in detail, and are typical of the connections at each of the other stations except the end station J. The station J has the usual bridging type of 35 telephone instrument. The wire 5 is cut at each station, and the terminals 6 and 7 thus formed are carried into the station. A connection 8 is also carried into the station from the wire 4.

40 The line-restorer 9 comprises the movable contact 10 in conjunction with the relatively stationary contact 11. When the line-restorer is to be automatically operated by the receiver hook 12, said contacts may be so 45 placed or mounted that the lowering of the receiver hook brings them together, whereas when the receiver hook rises they will separate so as to open the circuit. Any other suitable means for opening and closing these 50 contacts may be used without departing from the spirit of my invention.

The contact 10 connects to the terminal 6 by a wire 13, and the contact 11 connects to the terminal 7 by a wire 14. Therefore, 55 the lowering of the receiver hook and the simultaneous closing of the line-restorer serve to close the line wire 5 and to cut out the station E. Conversely the raising of the receiver hook will serve to open the line-restorer, and thereby open the line wire 5 and 60 cut in the station E.

A magneto generator 15 and bell 16 are provided for sending and receiving a call. The selector is designated by the numeral 65 17. Said selector includes six contacts 18,

19, 20, 21, 22 and 23 in conjunction with a button 24. In Fig. 1, said button is shown as having been fully inserted or moved toward the left, and it may be withdrawn or pulled out toward the right. This button 70 has a tapered or wedge-shaped end portion 25 which works between the extending portions of the contacts 19 and 22. When the button is fully inserted as shown in Fig. 1, the contact 19 is driven against the contact 18, and the contact 22 is driven against the contact 23, the contacts 19 and 22 being simultaneously disconnected from the contacts 20 and 21 respectively. On the other hand when the button is withdrawn toward the 80 right, the resiliency of the contacts 19 and 22 will carry them away from the contacts 18 and 23 respectively, and will carry them against the contacts 20 and 21 respectively. The contact 19 is connected by way of the 85 wires 14 and 26 with the right hand terminal 7 of the line wire 5, whereas the contact 22 is connected by means of the wires 13 and 27 to the left hand terminal 6 of the line wire 5. The contact 18 connects by the 90 wires 28 and 29 with the receiver hook, and the contact 20 connects by the wires 30 and 31 to the magneto contact 32. The contact 23 connects by the wires 33 and 31 to the contact 32 of the magneto, and the contact 95 21 connects by the wires 34 and 29 to the receiver hook.

The function of the button 24 is to reverse the positions of the contacts 19 and 22. The contact 32^a is one of the terminals of 100 the magneto. The other side of the magneto connects by the wires 35, 36 and 37 to the terminal 8 of the line wire 4. The terminals of the bell 16 connect respectively by the wire 38 to the receiver hook, and by the 105 wire 39 to the wire 36. When the magneto is actuated, the contact 32 is driven out against the contact 32^a. It, therefore, follows that, with the button fully inserted, the line-restorer being open, as shown in Fig. 110 1, the following circuits are established upon actuating the magneto; from the magneto, when actuated, through the contacts 32 and 32^a, wires 31 and 33, contact 23, contact 22, wires 27 and 13, to the terminal 6 115 of the line wire 5, through the called station and back over the line wire 4 to the terminal 8 and by the wires 37, 36 and 35 to the magneto. This establishes a ringing connection toward the left. At the same time there is 120 established another circuit as follows: from the line wire 4, through the terminal 8, and wires 37, 36 and 39 through the bell 16, through the wires 38, 29, and 28, contacts 18 and 19, and wires 26 and 14 to the terminal 125 7 of the line wire 5. This establishes a connection to receive an incoming call from the right side of the line. Also, the line-restorer being closed, a similar connection is established to the terminal 6 of the line wire 130

5. If the line-restorer is open, then a withdrawal of the button 24 toward the right will be found to reverse these connections, so that the outgoing current generated by 5 the magneto 15 will flow along the party line toward the right, while an incoming call from the left side of the line will ring the bell 16. When the line restorer is closed a ringing current from either side of the 10 line will actuate the bell 16, irrespective of the position of the button 24.

The receiver, transmitter, induction coil and battery are designated by the numerals 40, 41, 42 and 43 respectively. One side of 15 the receiver connects by the wire 44 to the wire 37 and, therefore, to the terminal 8 of the line wire 4. The other side of the receiver connects by the wire 45 to the secondary 46 of the induction coil. The common 20 connection 47 of the induction coil connects by a wire 48 to the contact 49 above the receiver hook. The uppermost contact 50 above the receiver hook connects by way of the wire 51 to the stationary contact 53 adjacent to the magneto. The lowermost receiver contact 54 connects by way of the wire 55 to one side of the transmitter, the other side of the transmitter connecting by the wire 56 to the battery, and the other side 25 30 of the battery connecting by the wire 57 to the free end of the primary of the induction coil. When the receiver hook is raised, all three of the contacts 49, 50 and 54 are brought together at the same time that the 35 line-restorer 9 is opened. The operation of the magneto serves to move the contact 32 away from the contact 53 and against the contact 32a.

Assuming the receiver hook to be raised, 40 the following circuits are found to be established: If the selector button 24 be fully inserted, as shown in Fig. 1, a talking circuit is established from the line wire 4 and terminal 8 through the wires 37 and 44 to the receiver 40, through the wire 45, secondary 46 and wire 48, through the contacts 49 and 50, through the wire 51, through the contacts 53 and 32, through the wires 52, 31 and 33, through the contacts 23 and 22, 45 50 through the wires 27 and 13 to the left hand terminal 6 of the line wire 5. The transmitter 41 is at the same time connected into this local circuit, including the wire 55, contacts 54 and 49, wire 48, primary of the induction coil, wire 57, battery 43, and wire 56.

If the button 24 be reversed in position so as to permit the contacts 19 and 22 to disengage from the contacts 18 and 23 respectively and connect with the contacts 20 and 60 21, it will be found that the talking circuit, including the receiver 40, and the transmitter 41, is reversed, so that said talking circuit is connected to the terminal 7 of the line wire 5, thereby permitting the conversation to be carried on over that portion of

the party line lying to the right hand side of the station E.

An examination of the disclosures thus far enumerated will show that the reversal of the position of the button 24, while the 70 line-restorer is open, will reverse the connection of the talking mechanism into connection with that portion of the party line lying in either the one direction or the other away from station E along the party line, 75 according to the position of the button. Furthermore, when the receiver hook is depressed so as to close the line-restorer, it will be found that station E can receive a ring from either direction on the party line, irrespective of the position of the button 24, whereas station E can, after opening the line-restorer, deliver a ring along the party line in the direction which may be predetermined by the position of the selector button 24. 80 85

Bearing in mind the fact that the connections at each of the stations B, C, D, F, G, H and J are the same in substance as those at the station E, it will be seen that the following results may be accomplished: Assuming the line to be clear on the right hand side of station E, including stations F, G, H and J, the station E selector button 24 being in the proper position, and the line-restorer being open, station E ringing circuit will be connected with the right hand side of the line, including stations F, G, H and J, so that a station on said portion of the line may be called by station E without disturbing the portion of the party line lying to the other side of station E, and including stations B, C, and D. In other words, the ringing impulses delivered from station E will pass along the party line in 90 95 that direction which is determined by the position of the selector button 24. Also the talking portion of station E is simultaneously connected to the same portion of the party line as that along which the ringing impulses are delivered. 100 105 110

Considering all of the foregoing facts, it will be seen that, by the arrangement thus far disclosed, it is possible to divide up the multiple party line into a series of more or less independent local talking and ringing circuits, which may be simultaneously employed, provided such local circuits do not overlap each other, but simply constitute 115 separate adjacent portions of the total party line. I will now disclose certain features of the invention which permit of ringing from one station past a number of other intermediate stations to a distant station, and which also permit of carrying on of a conversation with the station so rung, notwithstanding the fact that in so ringing and carrying on a conversation, it is necessary to jump over or overlap an intermediate 120 local circuit in the party line. 125 130

Interposed between the wires 31 and 52 is a key or button 58 which I will designate a "grounding ringing button." When said key stands normally in the raised position illustrated in Fig. 1, it establishes a connection between the wires 31 and 52. When, however, it is depressed it connects the wire 52 by a wire 59 to the ground connection 60. I have also provided another key or button 61 which I will call a "grounding talking button." This button normally stands in the raised position illustrated in Fig. 1, but when it is depressed it connects the wire 33 to the ground connection 60 by means of the wires 61^a and 62. It will be understood that each station may be provided with the aforementioned "grounding ringing" and "grounding talking" buttons. Assuming, for example, that a local conversation is being carried on between stations C and D, and that station E desires to call station B, the following procedure may be had: Station E will throw his selector button into the position shown in Fig. 1, which indicates that he is connected to that portion of the party line, including stations D, C and B. He will then raise his receiver and listen, and after ascertaining that stations C and D are using their portion of the circuit, he can call the central station A in the manner presently to be described, and explain that he desires to talk to station B. Central station A will then call B and explain the situation to him, whereupon B will depress his grounding talking button and will then be able to carry on a conversation with station E over a grounded circuit, simultaneously with, and irrespective of, the local conversation going on between stations C and D. While I have specifically mentioned connections between certain specified stations, still it will be understood that as far as this feature of the invention is concerned, similar connections and similar results may be accomplished with reference to other combinations of stations on the line. These proceedings may be had by reason of the following constructions: Station A is provided with a drop 63, one side of which is grounded by the wire 64 and the other side of which connects to the tip side 65 of a jack. The sleeve side 66 of the jack connects to the line wire 5. A special answering ringing plug 67 is provided, the sleeve side of which is grounded by a wire 68. When operator E turns his magneto, his grounding ringing button 58 being depressed, current is delivered over the circuit including contacts 32 and 32, wire 52, button 58, wires 59 and 60, ground, wire 64, drop 63, contact 65, line wire 4, wires 8, 37, 36 and 35 back to the magneto. When the operator at station A observes the dropping of his jack he

inserts his special plug, whereupon he may carry on a conversation with station E over the circuit including the tip side of the plug, contact 65, line wire 4, the wires 8 and 37, local E connections, wire 61^a, grounding talking button 61, wires 62 and 60, and through ground back to central station A. When operator A has ascertained from E that it is desired to call B, A will insert a plug of the ordinary type and ring B. A will then explain to B over a metallic circuit that E desires to talk to him on the grounded circuit and to press the grounding button, whereupon B will reverse his selector and be placed in direct grounded connection with E. During the ensuing conversation B and E will both retain their grounding talking buttons in closed position.

It will be observed that by means of the connections so far described the calling station is able to deliver his call in the same direction as that in which he desires to talk, without the necessity of reversing the position of the selector after ringing the desired station and before carrying on of the conversation. In the arrangement shown in Fig. 3 results similar to those heretofore described are secured with exception that in the present case the outgoing call is directed along the party line in the opposite direction from that in which the talking connection is established. Consequently it is necessary in the arrangement shown in Fig. 3 to reverse the selector between the ringing and talking operations. In the arrangement shown in Fig. 3 one side of the bell 16 connects to the line wire 4 by the wires 39, 36, 37 and 8. The other side of the bell connects by a wire 69 to the contact 53 of the magneto 15, the contact 32 connects by the wire 52 to the grounding ringing button 58, and said button connects by a wire 70 directly to the receiver hook 12 instead of through the selector as in the previous arrangement. Also the wire 36 connects to the magneto by the wire 35 as in the previous arrangement.

In Fig. 2 I have shown an arrangement similar to that of Fig. 1 with exception that the second line wire is dispensed with and the system operates purely as a grounded system. In this case the wires 36, 39 and 35 are connected to ground by the wires 71 and 72 respectively, this being equivalent to grounding the wire 35 of Fig. 1. With the arrangement shown in Fig. 2 it is not possible to carry on one local conversation between two stations, said conversation being superimposed over an intermediate local conversation between two intermediate stations, but many of the other operating possibilities of the arrangement shown in Fig. 1 may be accomplished. For example, with the arrangement shown in Fig. 2 the party line

may be divided up into a number of local circuits over which independent local conversations may be simultaneously carried on.

Referring to Fig. 4 I have therein illus-

5 trated a device for direct attachment to any of the well known forms of telephone instrument, said device including the selector and line-restorer contacts in convenient form. In this case the telephone instrument 10 is designated in its entirety by the numeral 73. The transmitter is shown at 74 and the receiver hook at 75. The attachment shown in the said figure includes a box-like structure 76, wherein are contained the selector contacts 15 and the terminals of the attachment, and a box-like structure 77, wherein are contained the line-restorer contacts. Working within the structure 77 is a vertically movable pin 78, the lower end of which may be conveniently attached to the receiver hook by means of a wire or the like 79, so that the raising and lowering of the receiver hook will move said pin up and down. The said pin carries a ring or collar 80, of insulating 20 material, which is adapted to engage one of the line-restorer contacts (for example, the contact 10). When the pin 78 is drawn down, the collar 80, by engaging the contact 10, drives the same against the contact 30 11, whereas when the receiver hook rises, the collar 80 permits the contact 10 to move away from the contact 11, as shown in Fig. 4.

The various selector contacts are mounted within the structure 76, and the button 24 35 projects from the side of said structure. Mounted within the structure 76 is a block of insulating material 81, on which are mounted the six terminals 82, 83, 84, 85, 86 and 87. The selector contacts 10, and 11, 40 are directly connected to the terminals 82 and 83, respectively. The terminals 82 and 83 correspond to the terminals 6 and 7, respectively, of Fig. 1. The contacts 86 and 87 correspond respectively to the wires 29 45 and 31 of Fig. 1. The terminals 84 and 85 are directly connected together within the structure 76. The terminal 84 corresponds to the terminal 8 of Fig. 1. The terminal 85 corresponds to the wire 39 of Fig. 1.

50 The terminal 82 is directly connected to the contact 22 of Fig. 1, and the terminal 83 is directly connected to the contact 19 of Fig. 1. These connections are made within the body of the structure 76.

55 When using the attachment just above described in connection with the usual form of telephone instrument, a series of circuits, such as those diagrammatically shown in the several figures, may be obtained, and the attachment above described serves simply as a 60 convenient means for bringing together within a compact structure certain of the contacts and connections.

While I have herein shown and described

only certain embodiments of my invention, 65 still I wish it distinctly understood that I do not limit myself to said embodiments except as I may do so in the claims.

I claim:

1. In a multiple party line, the combination with a pair of conductors, of a plurality of stations in connection therewith, each station including talking devices having transmitting and receiving instrumentalities, and each station including signaling devices having transmitting and receiving instrumentalities, line restoring means and selecting means for each station, each line restoring means being operable according to the position of the telephone receiver hook, and having contacts in series connection with one of the conductors, said contacts being in closed position when the telephone hook is down and being in open position when the telephone hook is up, the selecting means having commutating contacts bridged across the contacts of the line restoring means, permanent connections from one side of the talking devices to the other conductor, connections between the other side of the talking devices and the commutating contacts of the selecting means for connecting said side of the talking devices to either side of the line restoring means as desired according to the position of the selecting means, connections from one side of the signaling devices to the last mentioned conductor, and connections from the other side of the transmitting signaling devices for connecting the said devices simultaneously to the same contact of the line restoring means as is in communication with the talking devices when the selecting means is in any given position, means for temporarily grounding one side of the talking devices, and means for temporarily grounding one side of the signaling devices, for the purpose specified. 100

2. In a multiple party line, the combination with a pair of conductors, of a plurality of stations in connection therewith, each station including talking devices having transmitting and receiving instrumentalities, and each station having signaling devices including transmitting and receiving instrumentalities, line restoring means, selecting means for each station, connections for placing each line restoring means in series with one of the conductors, commutating contacts for the selecting means, connections from two of said contacts to the contacts of the line restoring means, permanent connections from one side of the talking devices and from one side of the signaling devices to the other conductor, connections from the other side of the talking devices, and from the other side of the transmitting signaling devices to desired contacts of the selecting means for the purpose of simultaneously connecting 115 120 125

6

the talking devices and the signaling devices to a selected contact of the line restoring means when the selecting means is in any given position, means for temporarily grounding said side of the talking devices, and means for temporarily grounding said side of the signaling devices, for the purpose specified.

pose specified.

3.. In a multiple party line, the combination with a pair of conductors, of a plurality of stations in connection therewith, each station including talking devices having transmitting and receiving instrumentalities and including signaling devices having transmitting and receiving instrumentalities, selecting means and line restoring means for each station, contacts in the line restoring means, connections for placing said contacts permanently in series with one conductor, commutating contacts in the selecting means, connections from said contacts to the contacts of the line restoring means, permanent connections from one side of the talking devices to the other conductor, permanent connections from one side of the signaling devices to said conductor, and connections from the other side of the talking devices and from the other side of the transmitting signaling devices to the selecting means for the purpose of simultaneously connecting the same to the same contact of the line restoring means when the selecting means is in any given position, for the purpose specified.

35 4. In a multiple party line, the combination with a pair of conductors, of a plural-
ity of stations in connection therewith, each station including talking devices having transmitting and receiving instrumentalities and including signaling devices having transmitting and receiving instrumentalities, line restoring means and selecting means for each station, each line restoring means having contacts, connections for placing said
40 45 contacts in series with one conductor, each selecting means having commutating contacts, connections from said contacts to the contacts of the line restoring means, permanent connections from one side of the talking devices and from one side of the signaling devices to the other conductor, connections from the other side of the talking devices to the selecting means for the purpose of connecting the same to either of the
50 55 contacts of the line restoring means according to the position of the selecting means, connections from the other side of the transmitting instrumentality of the signaling devices to the selecting means for the purpose
60 65 of delivering signaling impulses to the same contact of the line restorer as that to which the talking devices are connected when the selecting means stands in any given position, and connections from the receiving instrumentality of the signaling devices to

the other contact of the line restoring means when the selecting means stands in said position, for the purpose specified.

5. In a multiple party line, the combination with a pair of conductors, of a plurality of stations in connection therewith, each station including talking devices having transmitting and receiving instrumentalities and each station including signaling devices having transmitting and receiving instrumentalities, line restoring means and selecting means for each station, each line restoring means having a pair of contacts, connections for placing said contacts in series with one of the conductors, permanent connections from one side of the talking devices to the other conductor, permanent connections from one side of the signaling devices to said conductor, each selecting means having commutating contacts, connections from said contacts to the contacts of the line restoring means, connections from the other side of the talking devices to the selecting means for the purpose of connecting the same to either of the contacts according to the position of the selecting means, connections from the other side of the transmitting instrumentalities of the signaling devices to the selecting means for the purpose of simultaneously connecting the same to the same contact of the line restoring means as the talking devices when the selecting means is in any given position, connections from the other side of the receiving instrumentalities of the signaling devices to both of the contacts of the line restoring means when the same is in closed position, means for temporarily grounding the talking devices, and means for temporarily grounding the signaling devices, for the purpose specified. 105

6. In a multiple party line, the combination with a conductor, of a plurality of stations in connection therewith, each station including talking devices having sending and receiving instrumentalities and each station including signaling devices having transmitting and receiving instrumentalities, line restoring means and line selecting means for each station, each line restoring means having a pair of contacts, connections for placing said contacts in series with the conductor, permanent connections from one side of the talking devices to another conductor, permanent connections from one side of the signaling devices to said conductor, each selecting means having commutating contacts, connections from said contacts to the contacts of the line restoring means, connections from the other side of the talking devices to the selecting means for the purpose of connecting said side of the talking devices to either of the contacts of the line restoring means according to the position of the selecting means, connections from the other 130

side of the transmitting instrumentalities of the signaling devices to the selecting means for the purpose of simultaneously connecting the same to the same contact of 5 the line restoring means as the talking devices when the selecting means is in any given position, and connections from the other side of the receiving instrumentalities of the signaling devices to both of the contacts of the line restoring means when the same is in closed position, for the purpose specified.

7. In a multiple party line, the combination with a pair of conductors, one of which 15 is severable, of a plurality of stations in connection therewith, each station including talking devices having transmitting and receiving instrumentalities and each station including signaling devices having transmitting and receiving instrumentalities, line 20 restoring means and selecting means for each station, wires in connection with the line restoring means and the severable conductor for the purpose of controlling the severance of said conductor, wires in connection with the selecting means for the purpose of connecting one side of the talking devices to one end or the other of the severable conductor according to the position 25 of the selecting means, and for simultaneously connecting one side of the transmitting signaling devices to one end or the other of the severable conductor, and wires for connecting the other side of the signaling devices to another conductor, for the purpose specified.

5. In a multiple party line, the combination with a pair of conductors, one of which 30 is severable, of a plurality of stations in connection therewith, each station including talking devices having transmitting and receiving instrumentalities and each station including signaling devices having transmitting and receiving instrumentalities, line 35 restoring means and selecting means for each station, wires in connection with the line restoring means and the severable conductor for the purpose of controlling the severance of said conductor, wires in connection with the selecting means for the purpose of connecting one side of the talking devices to one end or the other of the severable conductor according to the position 40 of the selecting means, and for simultaneously connecting one side of the transmitting signaling devices to one end or the other of the severable conductor, and wires for connecting the other side of the signaling devices to another conductor, for the purpose specified.

10. In a multiple party line, the combination with a pair of conductors, one of which 45 is severable, of a plurality of stations in connection therewith, each station including talking devices having transmitting and receiving instrumentalities and each station including signaling devices having transmitting and receiving instrumentalities, line 50 restoring means and selecting means for each station, wires in connection with the line restoring means and the severable conductor for the purpose of controlling the severance of said conductor, wires in connection with the selecting means for the purpose of connecting one side of the talking devices to one end or the other of the severable conductor according to the position 55 of the selecting means, and for simultaneously connecting one side of the transmitting signaling devices to one end or the other of the severable conductor, and wires for connecting the other side of the signaling devices to another conductor, for the purpose specified.

15. In a multiple party line, the combination with a pair of conductors, one of which 60 is severable, of a plurality of stations in connection therewith, each station including talking devices having transmitting and receiving instrumentalities and each station including signaling devices having transmitting and receiving instrumentalities, line 65 restoring means and selecting means for each station, wires in connection with the line restoring means and the severable conductor for the purpose of controlling the severance of said conductor, wires in connection with the selecting means for the purpose of connecting one side of the talking devices to one end or the other of the severable conductor according to the position of the selecting means, and for simultaneously connecting one side of the transmitting signaling devices to one end or the other of the severable conductor, and wires for connecting the other side of the signaling devices to another conductor, for the purpose specified.

JOHAN SKINDERVIKEN.
